UNITED STATES PATENT OFFICE.

JOSEPH BLEWETT GRESSETT, JR., OF MERIDIAN, MISSISSIPPI.

RAILWAY-TIE.

1,273,217.

Specification of Letters Patent. Patented July 23, 1918.

Application filed December 18, 1917. Serial No. 207,775.

To all whom it may concern:

Be it known that I, JOSEPH B. GRESSETT, Jr., a citizen of the United States, and a resident of Meridian, in the county of Lauderdale and State of Mississippi, have invented certain new and useful Improvements in Railway-Ties, of which the following is a specification.

My invention is an improvement in railway ties, and has for its object to provide a tie which is composed of concrete, metal and wood, wherein the rails are supported on wooden blocks, which are independent of the tie, so far as vertical movement is concerned, to thoroughly support and cushion the rails, while at the same time without injury to the tie from shock and jar.

In the drawings:

Figure 1 is a perspective view of the improved tie;

Fig. 2 is a longitudinal vertical section;

Fig. 3 is a section on the line 3—3 of Fig. 2, looking in the direction of the arrow adjacent to the line;

Fig. 4 is a horizontal section; and

Fig. 5 is a perspective view of the metal portion removed.

In the present embodiment of the invention, a pair of sockets 1 and 2 is provided, the said sockets being similar but symmetrical, each socket opening at its inner end and being approximately U-shaped and consisting of an end and two side walls. Each socket has a lateral outwardly extending flange 3 at its bottom, and these flanges are braced against the side and end walls by triangular filler blocks 4, it being understood that each socket is an integral construction.

The end of each socket is tapering, being of greater length at its bottom than at its top, and gradually decreasing from the bottom to the top. Registering openings are provided in the side walls at the inner or open end of the socket, and through the registering openings is adapted to be passed a bolt 5, each bolt being engaged by a nut 6 to hold the parts in place.

Washers are arranged on each bolt between the heads and the concrete, and between the nut and the concrete. Wire cables 7 connect the bolts of the sockets of each tie, the ends of the cables being looped around the bolts as shown in Fig. 5. These cables 7 are spacing cables for holding the

sockets in proper relation with respect to each other during the molding of the tie.

The body 8 of the tie is formed from concrete, the said concrete being molded about the sockets, leaving the sockets open and leaving an open space, indicated at 9, between the sockets and extending longitudinally of the tie, and connecting the interiors of the sockets. In molding the ties, the sockets, connected by the cables 7, are placed in the mold in the proper relation, and the concrete is poured, suitable form boards being set up to provide the space 9. These sockets are arranged in the tie at the point where the rails will cross, and after the tie is sufficiently hard it is removed from the mold.

In placing the tie a shallow excavation, indicated at 10, is made at each socket, that is, beneath each rail, and each of these excavations is filled with slag, concrete, pebbles or the like, in such manner that the top of the bed so formed will be at the level of the road bed upon which the tie is adapted to rest. The tie is now placed over the beds in such manner that the rails will pass over the centers of the sockets or castings. These beds extend the full width of the tie and the length of the sockets.

It will be noticed that there are recesses 11 in the side faces of the tie at the heads of the bolts and at the nuts, to permit access to the heads and nuts. Wooden blocks 12 are mounted in the sockets, the said blocks fitting the sockets closely, and it will be noticed that the ends of the blocks are tapering as shown more particularly in Fig. 2. The blocks engage at one end the inner tapering face of the end wall of the socket and at the other end each block is engaged by the bolt 5, to prevent upward movement of the block, while permitting downward movement. The rails 13 rest upon these blocks which, in turn, rest upon the beds in the excavations 10, and the rails are spiked to the blocks, as indicated at 14. Each block extends approximately two inches above the level of the socket, that is, above the level of the top of the tie, and it will be evident that the entire weight of the rail is borne by the wooden block 12 and by the bed 10. Thus all shock and jar is taken off of the tie and when a block becomes worn or decayed, it may be easily removed and replaced by a new block. Should the beds

become defective this may be easily remedied. The ties are permanent, only the blocks being subjected to wear.

In forming the tie, the bolt openings are formed by a part of the mold which, when removed, leaves the registering openings in the concrete which permit the passing of the bolt through the concrete and into the socket casting. The cables not only space the sockets but give longitudinal strength and support to the tie.

I claim:

1. A cross tie comprising a body of concrete or the like, having a longitudinally extending opening opening at the top and bottom of the tie, a reinforcing socket at each end of the opening and open at its inner end, a wooden block in each opening and having its ends inclined to fit the inclined end of the socket; a bolt extending transversely of each socket at the open end thereof and engaging the block to hold it from displacement, and a connection between the bolts of each tie, said blocks being adapted for receiving the weight of the rails to take such weight from the tie.

2. A cross tie comprising a body of concrete or the like, having a longitudinally extending opening opening at the top and bottom of the tie, a reinforcing socket at each end of the opening and open at its inner end, a wooden block in each socket and hav-

ing its ends inclined to fit the inclined end of the socket, and a bolt extending transversely of each socket at the open end 35 thereof and engaging the block to hold it from displacement.

3. A railroad tie comprising a body of concrete having a vertical opening at each end, a reinforcing socket held in each opening, interchangeable blocks of fibrous material seated in the sockets and detachably held therein and freely movable downward, and means for limiting the upward movement of the blocks. 45

4. A railroad tie comprising a body of concrete having a vertical opening at each end, a reinforcing socket held in each opening, and interchangeable blocks of fibrous material seated in the sockets and detachably held therein and freely movable 50 downward.

5. A railroad tie comprising a body of concrete having a socket at each end, and interchangeable blocks of fibrous material seated in the sockets and detachably held therein and freely movable downward. 55

6. A railroad tie comprising a body of plastic material capable of hardening, having a vertical opening at each end, and interchangeable blocks of fibrous material seated in the openings and detachably held therein and freely movable downward. 60

JOSEPH BLEWETT GRESSETT, Jr.
